UNITED STATES PATENT OFFICE.

CHARLES G. SWANSON, OF CHICAGO, ILLINOIS.

ANTICLIMBING CONSTRUCTION FOR CARS.

1,258,061.

Specification of Letters Patent.

Patented Mar. 5, 1918.

Application filed October 31, 1914. Serial No. 869,542.

To all whom it may concern:

Be it known that I, CHARLES G. SWANSON, a citizen of the United States, residing at Chicago, in the county of Cook and State 5 of Illinois, have invented certain new and useful Improvements in Anticlimbing Constructions for Cars, of which the following is a specification.

My invention pertains to railway car construction and particularly to means for preventing, in case of extraordinary longitudinal shock as by collision or derailment, the climbing of one car upon another or upon the engine and the resultant demolishing of 15 the car bodies.

The rigid underframe of railway cars is not very liable to be injured under such circumstances, but the frame of one car is likely to rise and over-ride that of the next 20 adjacent car in the train, demolishing the less rigid superstructure or car body by an action commonly known as "telescoping," and it not infrequently happens that the car next the engine over-rides the engine and is 25 set on fire, adding the danger and loss from fire to that from impact.

By my invention I so construct the terminal portions of the underframe of the car that one is prevented from passing over or 30 beneath another by the engagement of such adjacent terminal portions, whereby the force of a collision, for instance, is sustained by the rigid underframe instead of acting upon the less rigid superstructure or 35 body and telescoping is prevented.

The invention as thus outlined will be readily understood from the following detailed description of a preferred embodiment of the same illustrated, by way of example, in the accompanying drawings, 40 wherein—

Figure 1, is a fragmentary longitudinal section through adjacent ends of two cars equipped with the invention;

Fig. 2, is a similar section through a combined platform and double body bolster casting on the line 2—2 of Fig. 3;

Fig. 3 is a detail end view of the parts shown in Fig. 2; and

Fig. 4 is a transverse section on the line 4—4 of Fig. 2.

In these drawings wherein similar reference numerals are applied to corresponding parts throughout, 11, 11 designates the adjacent ends of two cars coupled together in a train, the underframe of the cars including

each a combined platform and double body bolster casting having the longitudinal sill members 12 and the end sills or cross beams 12^a as well as the buffer beam 13, both of 60 which beams 12^a and 13 underlie the platform 14 and ordinarily project beyond the front end of the car body, extending transversely and substantially the full width of the car as shown in Fig. 3 and forming a 65 rigid and substantially integral part of the underframe.

The construction thus far described, and illustrated in Fig. 2 above the line of bolts shown in said figure, is well known in steel 70 cars. The underframe thus formed is very rigid and is adapted to sustain the longitudinal thrust or shock of collision, but it often happens that, instead of the buffer beams 13, 13 of adjacent cars striking squarely and 75 transmitting the force of the impact from one underframe to another, the beam of one car passes below or above that of the adjacent car and the force of the collision is expended upon the car body demolishing the 80 same. To obviate all danger of such "climbing" or over-riding of one car by another, I provide means upon the underframe of one car for engaging the beam of the adjacent 85 car.

As shown in Fig. 2, a pair of heels 15, 15 are securely bolted at 16 to the lower face of the forward portion of the longitudinal members 12 which heels extend downwardly and forwardly beneath the buffer beam 13. 90 This provides for equipping existing underframes of cars with the invention in such manner as to make the heels 15 substantially integral with the center sills of the car, but in case of original construction the center 95 sills of the body bolster may be so shaped as shown in Fig. 1 as to include the heels designated in said figure as 15^a, the result being substantially the same.

It will be understood that in the normal 100 working of the train the heels occupy the positions shown in full line in Fig. 1, but in case of one car striking an obstacle and coming to a sudden stop, the buffer beams 13 of the cars will abut one against another 105 and if the beam of the rear car rides over the beam of the forward car the heels of the rear car will engage with the buffer beam of the forward car as indicated in dotted lines in said Fig. 1, thus effectually 110 preventing the telescoping of the forward car. In case the buffer beam

13 should give way, the cross beam 12^a parallel and adjacent thereto serves as a reserve abutment to be engaged by the heels and acts in the same manner to prevent the climbing of the cars one upon another.

5 I claim—

1. In car construction, the combination with the car underframe including a transverse beam, of a heel forming a rigid portion of the underframe, the forward end of the heel extending no farther forward than the front face of the beam and adapted to engage the beam of the next adjacent car in a train in case of extreme longitudinal shock only to prevent the overriding of one car by the other.

2. In car construction, the combination with the car underframe including a transverse beam, of a heel forming a rigid portion of the underframe and extending forwardly in a horizontal plane below the plane of the beam and terminating short of the front face thereof, the forward end of the heel of one car in a train adapted to engage the beam of the next adjacent car in case of extreme longitudinal shock only to prevent the overriding of one car by the other.

3. In car construction, the combination with a car underframe including a transverse beam, of a pair of heels forming a rigid portion of the underframe and located upon each side of the longitudinal axis of the car, the forward ends of the heels of one car in a train extending no farther forward than the front face of the beam of such car and adapted to engage the beam of the next

adjacent car in case of extreme longitudinal shock only to prevent the overriding of one car by the other.

4. In car construction, the combination with a car underframe including a transverse beam, of a pair of heels forming a rigid portion of the underframe and located upon each side of the longitudinal axis of the car and extending forwardly in a horizontal plane below the plane of the beam and terminating short of the front face thereof, the forward ends of the heels of one car in a train adapted to engage the beam of the next adjacent car in case of extreme longitudinal shock only to prevent the overriding of one car by the other.

5. In car construction, the combination with a substantially integral combined platform and double body bolster casting forming a part of the underframe of a car and including a buffer beam, of a pair of heels rigidly connected with the body bolster casting of the underframe upon each side of the longitudinal axis of the car and extending forwardly beneath but short of the front face of the said beam, the heels of one car in a train adapted to engage the beam of the next adjacent car in case of extreme longitudinal shock only to prevent the overriding of one by the other, substantially as described.

CHARLES G. SWANSON.
